UNITED STATES PATENT OFFICE.

HOMER A. BUCKERT, OF ST. LOUIS, AND EARL K. HALL, OF UNIVERSITY CITY,
MISSOURI.

RECEDING OR DISAPPEARING CASTER OR ROLLER.

Application filed November 23, 1925. Serial No. 70,824.

Our invention relates to improvements in receding or disappearing casters or rollers, and has for its primary object a caster or roller for furniture, fixtures, furnishings, crates, cases, etc. and which is designed to support the article in such a manner that it will be raised above the floor when nominally loaded so as to permit it to be readily moved, but upon any additional weight being placed thereon the casters or rollers will recede or disappear into the support so that the major weight of the loaded article will be carried by its support.

Our device is especially useful for automobile creepers and the like, in that it permits the casters or rollers to move up into the body or base when any excessive weight has been placed thereon, such as in the case an automobile runs over the creeper. This permits the body of the creeper to sink to the floor and contact solidly therewith so that the vehicle can pass over the creeper without breaking the body thereof, and as soon as the vehicle has passed, the creeper will be raised from the floor due to the projection of the casters or rollers. This makes our device especially useful for garage and repair shop uses as it has frequently happened that with the old style of creeper, the mechanic neglected to remove the same to a secured place and a vehicle passing thereover would absolutely ruin the creeper because the body portion thereof was rigidly sustained at a predetermined distance above the floor. Our device, however, absolutely obviates any of this trouble.

A still further object is to equip furniture of any kind, whether for home, office or factory use, with casters or rollers so constructed that upon the article itself becoming weighted, for any reason whatsoever, the casters will recede or disappear or rather be pushed up into the support so that a firm foundation will be given the article, thus obviating any possibility of the casters or rollers, or the supports in which they are mounted, becoming broken and consequently useless.

By the use of our device any article may be mounted on casters or rollers so as to permit it to be readily moved about but at the same time, when any added weight other than that predetermined, is sustained by the article the casters or rollers will move upward into the support so that the article will have a solid and firm foundation but, when the weight on the article is removed, the casters will automatically resume their function.

This makes our device especially applicable to chairs, filing cabinets, bookcases, and similar articles, because none of these articles are to be moved while excessively loaded but, as soon as the excess load is removed, the casters will automatically spring into operation and permit ready moving of the article. In short, our device is designed to be applied to any article which requires moving and which is designed to carry a variable load so that when the excess load is removed, the casters or rollers, which are resiliently mounted, will be forced downward and come into action but, as soon as any load is placed on the article, they will recede or disappear and the load be supported by the article itself.

The drawing is a fragmental vertical section of our caster as secured in a support. In the drawing we have shown a housing 27, which is seated in a support 28. The housing is provided with a central opening 29 through which the shank 30 projects and which opening is sufficiently large to permit the shank to tilt when the roller recedes into the housing.

Surrounding the shank 30 is a plate 31, which may, or may not be provided with bearing balls 32 and which is provided with downwardly projecting ears 33. Mounted between the ears 33 is a bifurcated arm 34, the lower end of which carries a roller 35. The shank 30 is also carried by this arm and extends through the opening in the plate 31, which opening is of the same diameter approximately as the diameter of the opening 29.

Interposed between the plate 31 and arm 34 is a spring 36, which preferably surrounds the shank 30 although this is not necessary, the normal tendency of the spring being to push the roller 35 downward so as to raise the support 28 above the floor and permit the article to be moved around easily when no additional weight rests thereon. The bearing balls 32 when used permit the plate 31 to swivel readily and thus carry the roller 35 with it so that the article can be easily moved in any direction, the principal object being to provide any movable article, either household, office or factory, with a roller means resiliently mounted, said roller means permitting the article to be freely moved about under its own or a predetermined weight, but as soon as any additional weight other than that predetermined is placed on the article,

this additional weight will cause the article to sink down and rest on its supports so that at no time will the casters or rollers support this overweight, and by our construction all 5 breaking of the rollers or casters or their breaking out of the support or their collapse due to additional weight being placed on the article is eliminated, but at the same time any article supplied with these receding or disappearing casters or rollers can be readily moved about after the excess weight has been removed.

Having fully described our invention, what we claim is:—

- 15 1. In a device of the class described a support having a recess therein, a housing located in said recess, a plate rotatably mounted in said housing, an arm pivotally secured at one end to said plate, a roller carried by the opposite end of said arm, a shank carried by said arm and extending through said plate and housing, and means located between said arm and said plate and surrounding said shank for normally causing said roller to project below said housing.
- 20 2. In a device of the class described a support having a recess therein, a housing located in said recess, a plate rotatably mounted in said housing, an arm pivotally secured at one end to said plate, a roller carried by the opposite end of said arm, means located between said arm and said plate for normally

- 30

causing said roller to project below said housing, and means for limiting the projection of the roller.

35 3. In a device of the class described a support provided with a recess in its underneath surface, a housing opened at its bottom located in said recess, an arm pivotally secured at one end located in said housing, means for rotatably securing said arm in said housing, a roller carried by the free end of said arm and adapted to normally project below said housing and support, and resilient means within said housing for yieldingly holding said roller in normally projected position.

40 4. In a device of the class described a support provided with a recess in its underneath surface, a housing opened at its bottom located in said recess, an arm pivotally secured at one end located in said housing, means for rotatably securing said arm in said housing, a roller carried by the free end of said arm and adapted to normally project below said housing and support, resilient means within said housing for yieldingly holding said roller in normally projected position, and means for limiting the amount of projection of the roller.

45 50 55 In testimony whereof we have affixed our signatures.

HOMER A. BUCKERT.
EARL K. HALL.
